REVIVING OR INCREASING THE PRODUCTION OF CLOGGED OR CONGESTED OIL WELLS

Charles S. Ackley, Brooklyn, N. Y., assignor to Thermactor Company, New York, N. Y., a corporation of Delaware

Application December 16, 1949, Serial No. 133,384

1 Claim. (Cl. 166—23)

1

The invention herein disclosed relates to the reactivation of oil wells which have lost production or become dormant through the clogging action within the oil sand of congealing wax, gum or sludge present in the oil.

The refrigeration effected by expansion of the volatile constituents of a flowing well always has an adverse effect tending to make a well seal itself off, and it is common knowledge that the oil left in a well at the end of what may be considered economical production, is usually much more than that taken out.

The present invention has been developed particularly with a view to restoring such non-productive though actually valuable, dormant wells to economical and profitable production.

Particularly it is a purpose of the invention to accomplish such results with a minimum of new equipment and expense and with full utilization of the well equipment that may be in place in such dormant, abandoned or other like wells.

Other special objects of the invention are to effect liquification and reduction of viscosity of the materials causing the clogging action within the sand and in so doing, to create and maintain a hot oil pool spreading from the well into the surrounding structure and serving thereby as a restoring agent and as an increasing and sustaining reservoir of production oil.

Further special objects in this connection are to provide satisfactory controls for maintaining the hot oil pool so created more or less constant in the extent to which it can be supported by the adjacent or surrounding structure.

Other desirable objects attained by the invention are set forth and will appear in the course of the following specification defining and broadly covering the invention.

The drawings accompanying and forming part of the specification illustrate certain present practical embodiments of the invention. Structure and arrangement, however, may be modified and changed as regards such illustration, all within the true intent and broad scope of the invention as hereinafter defined and claimed.

Fig. 1 in the drawings is a broken sectional view illustrating diagrammatically installation and operation of the invention for increasing production in a producing well having a declining rate of production;

Fig. 2 is a similar view showing features of the invention as installed in one of the pressurizing wells of a secondary recovery system;

Fig. 3 is a broken part sectional and perspective view illustrating diagrammatically a typical five spot layout embodying the invention.

2

In the case of a well which is actually producing, but at a declining rate, the invention may be applied substantially as shown in Fig. 1.

In this view a cased oil well is indicated, having a perforated liner 5 in the oil sand at the lower end of the casing 6.

A well head 7 is shown applied to the casing, designed to pass the flow tubing and power cable for the electric heater carried by the tubing.

10 This heater, as more fully disclosed in copending patent application Serial No. 126,089, filed November 8, 1949, now Patent No. 2,632,836, is of novel construction, particularly in that it is of open tubular formation having an open, inner length of tubing 8 designed to match and be connected to the flow tubing 9 by the regular couplings 10, and an outer sheath or casing 11 of less diameter than the well liner so as to freely pass fluid interiorly and exteriorly.

15 The electric heating elements are disposed within the elongated annular chamber provided between the inner and outer shells of the heater, supplied by power cable 12 extended up alongside the flow tube and supported at intervals by clamps 13 loosely seated on the couplings 10.

20 A thermostat set to maintain a desired mean temperature is indicated at 14, mounted on the upper end of the heater.

25 A pump is shown at 15 connected in the flow tubing above the heater, adapted to be operated in the usual way by sucker rods 16.

The well head may have a stuffing box or equivalent at 17 for packing the flow tubing, and a stuffing box or the like at 18 for the power cable, so as to seal off the annular well space about the heater, pump and flow tubing.

30 The heater is lowered by the flow tubing to a position well down in the oil bearing sand and, if necessary, the well is primed with a few barrels of oil to make sure of completely submerging the heater.

35 With the thermostatic control means set to maintain a desired mean temperature, preferably at a level above the melting point of the waxy and gummy constituents of the oil and below the gasification temperature of the lighter components of the oil, the heater may be left on as long as need be to dissolve the congealed materials and cause the thinned, heated oil to penetrate and impart its heat to the surrounding structure to create more or less of a spreading pool of hot oil.

40 As this heated body expands and works back into the structure, more and more of the blocked or congealed oil is released to flow back into the well and rise in the casing and flow tubing.

There is, however, a limit to which the heated oil will work outwardly from the well by natural pressure, because due to friction in the sand a balance point is reached that will arrest further outward movement and spread of the hot oil pool.

The time required for building up a sufficient pool of the hot oil will vary with different structures and the extent to which a producing well may have been depleted.

At any rate, pumping may be started and maintained continuously or intermittently and at a rate proportionate to the build-up of the pool.

Preferably heating and pumping operations are so coordinated as to surely maintain the heater covered at all times with oil.

Also, it is important to remove the oil at a rate sufficient to prevent the hot oil from rising much above the oil sand to avoid heat transfer through the casing to the cooler, surrounding ground barren of oil.

To maintain the oil level at or as near the top of the oil sand as possible, the speed of operation of the pump may be governed, or in some instances the pump may be operated for several hours and then shut down, in effect maintaining successive cycles of pumping and heating. Or heating may be continued and pumping effected intermittently, or pumping continued and heating applied in successive intervals, the invention enabling choice of these conditions to meet different situations.

Generally the overburden affords complete insulation, enabling effective application of heat to maintain the maximum reservoir of hot oil which the structure will support.

This hot oil is the more readily removed by the pump, so the pump is to that extent rendered the more effective. The flow tubing is completely open straight down through the heater and this also is a factor in increasing the recovery rate.

In dormant wells, which have ceased to produce and been abandoned, the same hot pooling method may be followed and the expenses involved may generally be justified, considering that such wells may retain usually from 40% to 70% of the primary oil in the reservoir. These wells, in most or many cases, have become dormant because of blocked pores filled with wax, sludge or congealed oil which have gradually sealed the porous sand structure and stopped movement of oil through the well.

At the time of abandonment the casing may have been removed and the wells left to cave or fill in with earth and water. To revive such wells involves cleaning out and re-casing to the oil sand, but this ordinarily may be less costly than drilling new wells. In many cases these abandoned wells are left with the casing in place. Unless wells have been abandoned because of the intrusion of salt water into the oil sand, they may profitably be reconditioned under the present invention, utilizing the structure and plan outlined in Figs. 2 and 3.

This may be a pressurizing operation such as practiced in secondary recovery fields, with a number of pressurizing wells grouped about a more or less centrally located outlet well.

A typical arrangement of this character is indicated in Fig. 3, with four pressure injecting wells 19 grouped in the pattern of a square or rectangle about a substantially centrally located outlet well 20.

Flow tubing 9 carrying the open tubular heaters as previously described, are installed in the pres-

sure wells and the outlet well which is cased and has a perforated liner at the bottom, may be left open and be connected and arranged for delivery of oil to storage or tankage.

5 To revive and restore flow of oil from such a well may require an appreciable length of time, as the sand structure in such a location must be thoroughly warmed to in effect thaw out and liquify the waxes or congealed oil by which the sand is sealed. The wells containing the heaters may be primed with oil from the surface from time to time, as required to keep the heaters covered. This oil may be introduced through the flow tubing.

10 15 In this installation, with no pump or pumping gear, the flow tubing to which the heater is attached has a continuous, unobstructed passage through it from top to bottom. This enables the tubing to be used for gaging the depth of oil accumulating within it.

Before pressurizing, the wells are sealed off at approximately the upper sand level by packers 21 closing the annular well space between the casing and flow tubing. These packers, as indicated in Fig. 2, may have suitable stuffing boxes 22 or the like for sealing the power cables therethrough.

25 30 After gaging the depth of oil in the open flow tubing and determining that a sufficient pool of hot oil has been built up around and above the heater, the well head 7 may be attached, ready for pressurizing.

The well head in this case may carry a pressure line 23 and a relief line 24 connected with 35 40 the flow tubing and equipped with check valve 26, pressure gage 25, pressure relief valve 27 and possibly other accessories, as required.

Natural gas, if available, or compressed air 45 50 may be used as the pressure fluid. This pressurizing fluid introduced through the flow tubing under pressure high enough to prevent the entry of well oil into the flow tubing at 8 will, upon contact with the hot inner tube of the heater, expand and come into contact with the heated oil within the well and surrounding oil structure. The expansive force of the hot gas drives the heated oil further and further into the congested structure.

The pool of oil surrounding the heater may be 55 60 replenished from time to time, to take the place of the oil forced back into the structure, by introducing oil, as required, with the pressurizing gas.

Control of pressure and temperature may be effected under guidance of the recording of surface instruments to attain the best results.

The pressurized oil reaching the outlet well may be delivered under its own pressure or be pumped to a surface pipe line or to tankage.

65 60 In this case also the heating of the oil facilitates delivery operations and prevents deposit of paraffin or other effects that might impede or slow up the action.

The invention thus differs materially from cold water and other pressurizing operations which may tend to chill and congeal the petroliferous products instead of thinning and rendering them the more fluid.

70 75 The output of the production well may be controlled or kept at such a rate as will maintain the level of heated oil in the pressurized well above the heater therein and maintain the hot oil pool surrounding the pressurized well.

The new equipment required for practicing the invention is relatively simple and can be used in

conjunction with the existing well equipment. Operations are readily controlled in different ways to meet special conditions in different locations. The straight through, open construction of the heaters and their mounting on the flow tubing provide for free flow of fluid in either direction, as may be required for different operations.

While natural gas or compressed air have been mentioned as the pressurizing fluids, it is possible also that water may be used for this purpose.

What is claimed is:

The herein disclosed method of reviving or increasing the production of petroleum in locations having adjoining wells reaching the same oil sand and more or less clogged by congealed products and comprising providing flow tubing and tubular heater having a continuous, open flow passage therethrough of the same extent and introducing said flow tubing and tubular heater into one well to a depth with the heater in the oil sand locale, packing off that well about the flow tubing substantially at the upper level of the oil sand, energizing the heater to liquify and reduce the viscosity of petroliferous products in said well and immediately surrounding structure to form a hot oil pool and forcing a pressure fluid down through said flow tubing and out through the corresponding fully open flow passage of said tubular heater into the hot pool of oil created by said heater in the packed-off portion of the well and the surrounding structure to

thereby enforce migration of the lowered viscosity pool contents to the well adjoining and open to the same oil sand, controlling the heater in temperature and time to maintain temperature of the heated oil in the pressurized well above the melting point of waxes and gums and below the gasifying temperature of volatile constituents of the oil, and controlling output of said adjoining well at a rate to maintain the level of heated oil in the pressurized well above the heater and to maintain the hot oil pool surrounding the pressurized well.
